UNITED STATES PATENT OFFICE.

SIDNEY J. EGINTON, OF BRADFORD, PENNSYLVANIA.

OIL-PUMP.

SPECIFICATION forming part of Letters Patent No. 364,232, dated June 7, 1887.

Application filed March 19, 1887. Serial No. 231,569. (No model.)

To all whom it may concern:

Be it known that I, SIDNEY J. EGINTON, a citizen of the United States, residing at Bradford, in the county of McKean and State of 5 Pennsylvania, have invented a new and useful Improvement in Oil-Pumps, of which the following is a specification.

My invention relates to an improvement in oil-pump apparatus; and it consists in the peculiar construction and combination of devices, that will be more fully set forth hereinafter, and particularly pointed out in the claims.

In the drawings, Figure 1 is an elevation of a rig for pumping oil. Fig. 2 is a vertical sectional view of my improved oil-pump apparatus. Fig. 3 is a detailed perspective view of the sleeve for connecting the tubing with the stand-pipe and suspending the tubing from the upper end of the casing.

20 In Fig. 1, *a* represents the derrick or hoist. *b* represents the walking-beam attached to the upper end of the plunger-rod *c*. *d* represents the steam-engine or other motor, the fly-wheel of which is connected to one of the walking-beams by means of a pitman, *e*, so that the walking-beam will be oscillated when the fly-wheel rotates, and thereby cause the plunger-rod *c* to reciprocate in the pump-tubing. All of this is of the usual well-known construction.

30 *A* represents the casing of the oil-well, the upper end of which projects above the level of the ground, and is provided with the screw-threads *B*.

C represents an annular collar, which is 35 screwed on the upper end of the casing and is provided with an annular vertical upwardly-projecting flange, *D*.

E represents a circular plate, which fits on the upper end of the casing and in the circular space in the annular collar formed by the flange *D*. In the center of the plate *E* is a vertical opening, *F*.

40 *G* represents a vertical sleeve, which extends downward through the opening *F*, and is provided at a suitable distance from its upper end with an annular projecting collar or flange, *H*, which is formed integrally with the sleeve and bears upon the upper side of the plate *E*. The upper end of the said sleeve is provided with 45 a countersunk enlargement which is screw-threaded, and the lower end of the said sleeve, which extends downward in the casing for a

considerable distance below the plate *E*, is provided with a similar countersunk enlargement having a screw-thread.

55 *I* represents the pump-tubing, which extends downward in the casing to the oil in the well, and the upper end of the said tubing is screwed to the depending lower end of the sleeve *G*, and thereby the said tubing is supported by the said sleeve and is suspended from the upper end of the casing.

To the upper end of the sleeve is screwed a vertical stand-pipe, *K*. The bore of the sleeve corresponds in size to the bore of the 65 tubing and of the stand-pipe, and thereby the plunger attached to the plunger-rod *c*, and not shown herein, as it is of the usual construction, is adapted to be drawn up through the tubing by the derrick or hoist when necessary. The 70 upper end of the stand-pipe is closed and is provided with the packing-box *L*, through which the plunger-rod extends. From one side of the stand-pipe, and communicating with the same, extends a discharge-pipe, *M*, which 75 leads to a suitable tank or other receptacle for the oil.

The reciprocating motion of the plunger-rod necessarily imparts a vibratory motion to the stand-pipe, and this in time causes the upper 80 end of the sleeve *G* to break off just above the collar or flange *H*. Heretofore these sleeves *G* have not been provided with the depending lower end, and the upper end of the tubing *I* has been screwed in the upper portion of the 85 sleeve, just below the lower end of the stand-pipe. The defect resulting from this construction is that when the upper portion of the sleeve breaks, the tubing, which is entirely supported and suspended by the said sleeve, becomes detached and drops down into the well, thus entailing a great expenditure of time, labor, and money in order to fish it up from the well. I provide the sleeve with the depending lower end, *G'*, as shown in Figs. 2 and 3, 90 and couple the upper end of the pump-tubing to the lower end of the said depending portion of the sleeve, and thereby separate the upper end of the tubing from the lower end of the stand-pipe by a considerable distance. As the 95 lower portion, *G'*, on the sleeve fits snugly in the opening *F* of the circular plate, the sleeve is prevented from vibrating with the stand-pipe, and thereby there is no danger of the up-

per end of the tubing becoming uncoupled from the lower end of the sleeve, and this also causes the strain exerted by the vibrating stand-pipe to be borne by the upper projecting portion of the sleeve, thereby causing the latter, when it breaks, to part just above the collar or flange H, leaving the lower portion of the sleeve intact, and thus preventing the tubing I from becoming disengaged and dropping in the well.

Having thus described my invention, I claim—

1. In an oil-pump apparatus, the coupling-sleeve G, adapted for the attachment of the stand-pipe and provided with the outwardly-projecting supporting flange H, to rest on the supporting-plate, and the lower portion, G', depending below the said flange and adapted for the attachment of the pump-tubing, substantially as described.
2. In an oil-pump apparatus, the combination

of the casing A, the plate E on the upper side of the casing, having the central opening, the sleeve G, having the depending portion G' extending through and fitting snugly in the opening in the plate E, the said sleeve being further provided with the flange H, bearing on the upper side of the plate E to support the sleeve, the upper portion projecting above the said flange, the pump-tubing I, coupled to the lower depending portion, G', of the sleeve, and the stand-pipe K, coupled to the upper projecting end of the sleeve, all combined and arranged to operate substantially in the manner and for the purpose described.

In testimony that I claim the foregoing as my own I have hereto affixed my signature in presence of two witnesses.

SIDNEY J. EGINTON.
